(57) **CLAIM**

The ornamental design for a nozzle, as shown and described.

DESCRIPTION

FIG. 1 is a perspective view of a nozzle of the new design;

FIG. 2 is a front elevational view of the nozzle of FIG. 1;

FIG. 3 is a left side elevational view of the nozzle of FIG. 1;

FIG. 4 is a right side elevational view of the nozzle of FIG. 1;

FIG. 5 is a top plan view of the nozzle of FIG. 1; and,

FIG. 6 is a bottom plan view of the nozzle of FIG. 1.

The portions of the Figures shown in broken lines are not part of the claimed design and are for illustration only.
